UNITED STATES PATENT OFFICE.

FRANK ANTHONY HEADSON, OF LAFAYETTE, INDIANA.

ROTARY ENGINE.

No. 805,545.

Specification of Letters Patent.

Patented Nov. 28, 1905.

Application filed January 13, 1904. Serial No. 188,911.

To all whom it may concern:

Be it known that I, FRANK ANTHONY HEADSON, a citizen of the United States, residing at Lafayette, in the county of Tippecanoe and State of Indiana, have invented certain new and useful Improvements in Rotary Engines, of which the following is a specification.

This invention relates to that class of engines popularly designated and known as "rotary" engines in which the rotating part is a rotatable piston-head provided with a plurality of wings or blades against which the motive fluid impinges, and particularly to the construction, arrangement, and means of positively operating these wings, all of which will be more fully hereinafter set forth.

The principal object of the invention is to provide a simple, economical, and efficient rotary engine.

20 A further object of the invention is to provide a rotary engine having a rotatable piston-head and two or more pivoted blades with eccentric mechanism for positively operating the same.

25 Further objects of the invention will appear from an examination of the drawings and the following description and claims.

The invention consists principally in a rotary engine in which there are combined a cylinder provided with a fluid-pressure chamber, a piston-head rotatably mounted therein, wing mechanism pivotally mounted thereon, a rock-shaft for and upon which each of such wings is mounted, and means for positively 35 operating these shafts by and during the rotation of the head.

The invention consists, further, in a rotary engine in which there are combined a cylinder provided with a fluid-pressure chamber, 40 a rotatable piston-head mounted therein, a plurality of pivoted wings thereon, arranged to swing so that their outer edges describe a true circle around the axial center of the pressure-chamber, although they move toward 45 and from the center of the piston-head, a rock-shaft for and upon which each of such blades is mounted, and eccentric mechanism connected with such shafts to operate the same by and during the rotation of the head.

50 The invention consists, further and finally, in the features, combinations, and details of construction hereinafter described and claimed.

In the accompanying drawings, Figure 1 is 55 a longitudinal sectional elevation taken on line 2 of Fig. 2 looking in the direction of the ar-

row; Fig. 2, a transverse sectional elevation taken on line 3 of Fig. 1 looking in the direction of the arrow; Fig. 3, a developed plan view of a portion of the periphery of the rotatable piston-head, showing the cut-off valves and arrangement thereof; Fig. 4, a transverse sectional elevation taken on line 5 of Fig. 1 looking in the direction of the arrow; Fig. 5, a transverse sectional elevation taken on line 6 of Fig. 1 looking in the direction of the arrow; Fig. 6, an enlarged developed plan view of one of the cut-off valves and pocket in which it operates; Fig. 7, a perspective view of one end of the main shaft of the engine with the piston-head removed and showing the pivoted swinging blades with their operative mechanisms, and Fig. 8 a similar view of the other end of the main shaft of the engine.

75

In constructing an engine in accordance with these improvements I make a base portion *a* of the desired size, shape, and strength to hold and support the separate cylinder *b* in position. The cylinder and base portions, 80 as above suggested, are made separable—that is, in two parts bolted together—so that they may be more easily molded in the first instance and finished afterward. The cylinder of course, as will be understood in all of such 85 engines, is provided with a cylindrical fluid-pressure chamber *c*, in which is rotatably and eccentrically mounted a piston-head *d*, by means of a main shaft *e*, which is journaled and rotatably mounted in bearings *f*, secured 90 to the end walls *g*. As is usual in such constructions, it is well known that it is very difficult to bore out the bearing-boxes for the main shaft in such a manner that they are always in correct alinement with the center of 95 the piston-head, so as to prevent cramping. In order to compensate or provide for irregularities in the castings or bad workmanship, these bearing-boxes are adjustably secured to the end walls by means of bolts *h*, which take 100 the larger portion of the strains, while a plurality of set or adjusting screws *i* is provided to contact the plate in such a manner as to bring it to the desired alinement, all of which will be appreciated and understood by those skilled 105 in the art.

To provide means by which the potential energy of the motive fluid may be transformed into work done—that is, the rotation of the piston-head, its shaft, and other parts— 110 two wings *j* are provided and made in the form of sectors of a circle operating in grooves

l in the piston-head, beginning at a point near the periphery and ending at a point at or near the center. To positively operate these grooved wings, they are provided with 5 arms *l*, extending in one direction therefrom and secured to rock-shafts *m*, in turn movably mounted in the piston-head at a point coincident, or substantially so, with the center from which the curves of the wings are 10 struck, the arrangement being such that as these rock-shafts are rotated the wings, through the media of their arms, are likewise moved inwardly or outwardly, as the case may be. It becomes desirable to provide means 15 by which these rock-shafts may be operated at the proper time. In order to accomplish this result, an eccentric *n* is provided near each end of the main shaft and preferably immovably secured to the end cylinder at the 20 right degree, being cylindrical and arranged concentric with the axis of the pressure-chamber. This eccentric is provided with an eccentric-strap *o*, having an arm extending out therefrom and pivotally connected with a lever-arm *p* and one end of its respective rock-shaft. It will be noticed on inspecting Figs. 25 1, 7, and 8 that the eccentric for one rock-shaft is at one end of the cylinder and the eccentric for the other rock-shaft at the other end. Examining Figs. 1, 7, and 8, it will be seen that 30 as the piston with its head rotates the strap is carried around thereby, and as such eccentric-strap is carried around its position diametrically is changed, all of which acts to operate the lever-arm *p* and move the proper wing in or out, as the case may be. It will be seen also that the 35 movement of the wings is positive and not depending upon the action of springs or fluid-pressure and that each wing has two distinct 40 pivotal centers or pivotal connections moving in different paths. The inner pivotal point or individual inner pivotal center of each of the wings is at the point where it is connected with the piston-head, and its path of motion is concentric with the axis of the piston-head, while 45 each wing is indirectly by means of its rock-shaft and lever-arm connections pivoted at a point in alignment with the outer edge of such wing, so that such outer edge describes a true 50 circle around the axial center of the pressure-chamber and is constantly at the same distance from its axial center, the wings thus having an oscillating movement, while the outer edges move simply in a true circle. As 55 a consequence the shocks and jars usually found in such constructions are largely obviated. It is further desirable that these eccentricities, with their straps and connecting lever-arms, be made to operate in such a manner as to largely minimize all friction and 60 shut them off practically from all contact with the motive fluid. To accomplish this, the piston-head is provided with two circular partitions or flanges *q*, one at each end, which 65 are of considerably larger diameter than the

piston-head and are arranged concentric therewith, so as to span or hermetically seal with the aid of packing-rings *r* the fluid-pressure chamber and at the same time form chambers *s* between them and the end walls of the cylinder. An inspection of Fig. 1 will show that the eccentricities, with their straps and connecting lever-arms, are arranged in such chambers and that whenever desirable such chambers can be entirely or partially filled with a lubricant, thereby lessening objectionable adhesion and the development of frictional force. 70

An inspection of Figs. 4 and 5 will show that the piston-head is arranged eccentric with the fluid-pressure chamber and that, relatively speaking, its lower peripheral surface contacts the lower peripheral surface of the walls that form the fluid-pressure chamber and that a steam-inlet *t* is arranged in the lower walls of the cylinder at a point where 80 the outer periphery of the piston-head contacts therewith, so that at certain times such inlet is cut off and at other times opened, thereby providing a construction by which the expansibility of the motive fluid may be 85 taken advantage of. The peripheral surface of the piston-head is provided with one or more steam-pockets *u*, in which cut-off valves *v* may be arranged which slide longitudinally thereof. These cut-off valves, as shown in 90 the developed Figs. 3 and 6, are in the nature of slides engaging with dovetails *w*, longitudinally arranged in the pockets, so that the valves may move across the same. The valves are provided with substantially triangular grooves *x*, so that as the position thereof is changed with regard to the inlet-opening *t* in the walls of the cylinder the fluid-pressure may be cut off at any desired point and 95 permit the remainder to act expansibly. 100 These valves are connected together and to a valve-rod *y* by means of a pin *z*, diametrically passed through the piston-head and through an opening or perforation 10 in the main shaft. 105

The main shaft carries two fly-wheels 11 and 12, as shown in Fig. 1, and the fly-wheel 12 contains a fly-wheel governor connected with the valve-rod *y* to move the same inwardly and outwardly at the desired times. As the 110 fly-wheel governor is no part of this invention, and as a preferred form thereof is described and claimed in Patent No. 678,469, issued to me the 16th day of July, 1901, I do not deem it necessary to illustrate or further 115 describe the same herein. It is sufficient to say that as the speed increases the valve-rod will be moved in one direction to operate the cut-off valve the desired amount and cut off the admission of steam at the desired point, while when the speed decreases a desired 120 amount the valve-rod is moved in an opposite direction to operate the cut-off valve likewise, and the point of the cut-off is changed 125 or delayed. 130

The motive fluid is exhausted through an exhaust-opening 13, which contains a "bypass" 14 to assist in the exhaust thereof from the groove and pocket of the cut-off valve.

- 5 In order to prevent the steam from passing by the wing, as shown in Fig. 4, the heel or outer edge of such wing is provided with a packing-strip 15, which is longer than the wing and is arranged to always bear on the inner 10 surface 16 of the fluid-pressure chamber, as shown particularly in Figs. 1 and 4, such arrangement permitting the heel or outer edge of the wing to contact the inner peripheral surface of the fluid-pressure chamber when 15 the parts are in the position shown in the upper part of Fig. 4—that is, to be impacted by the motive fluid and assist in keeping it out of contact with the lower inner surface of the fluid-pressure chamber when the parts are in 20 the position shown in the lower part of such figure. It will be seen to the right of Fig. 5 that the parts have just finished taking steam and that the upper wing is being acted on by the expansion of the motive fluid, and that 25 such action will continue until such wing passes the exhaust-port, when the motive fluid will be allowed to escape. An inspection of the same figure will also show, should the parts be stationary, that the engine could not 30 be started—in other words, it would be on center. To provide means for starting the engine at such point, a by-pass 18 is provided, which connects the inlet-opening with a point not contacted by the outer surface of the per- 35 iphal head. A supplementary valve 17 is provided, the opening or closing of which controls the by-pass. The opening of this valve will permit a portion of the motive fluid to enter such chamber and rotate the engine. 40 When the parts have been rotated or operated to acquire sufficient momentum, this valve may be closed, when the steam or other motive fluid will enter in the usual manner.

I claim—

- 45 1. In a rotary engine, the combination of a cylinder provided with a fluid-pressure chamber and fluid-inlet passage, a piston-head rotatably mounted therein in sliding contact with the inner surface of the cylinder between 50 the fluid-inlet passage and the pressure-chamber, wing mechanism pivotally mounted on such head, and means for positively swinging such wing mechanism by and during the rotation of the head, substantially as described. 55 2. In a rotary engine, the combination of a cylinder provided with a fluid-pressure chamber and fluid-inlet passage, a piston-head rotatably mounted therein in sliding contact with the inner surface of the cylinder between 60 the inner opening of the fluid-inlet passage and the pressure-chamber, a plurality of wings pivotally mounted on such head, and eccentric mechanism for positively swinging such wing mechanism by and during the rotation 65 of the head, substantially as described.

3. In a rotary engine, the combination of a cylinder provided with a fluid-pressure chamber and fluid-inlet port, a piston-head rotatably mounted therein in sliding contact with the inner surface of the cylinder on all sides of 70 the inlet-port and provided with steam-pockets in operative connection with the inlet-port, a plurality of wings operating in such piston-head, a rock-shaft for each of such wings rockingly mounted in the piston-head, and 75 means for operating each of such rock-shafts positively by and during the rotation of the head, substantially as described.

4. In a rotary engine, the combination of a cylinder provided with a fluid-pressure chamber and fluid-inlet port, a piston-head rotatably mounted therein in sliding contact with such cylinder and provided with valve-pockets adapted to communicate with the inlet-port, 80 curved wings operating in grooves in the piston-head, a rock-shaft for each of such wings and to which such wings are rigidly secured and rockingly mounted in the piston-head, and eccentric mechanism connected with such 85 rock-shafts and arranged to be positively operated by and during the rotation of the piston-head, substantially as described. 90

5. In a rotary engine, the combination of a cylinder provided with a fluid-pressure chamber and fluid-inlet port, a piston-head rotatably 95 mounted therein in sliding contact with one side of the cylinder and provided with a plurality of pockets, a valve movably mounted in each pocket provided with a steam-pocket therein, means for automatically moving such 100 valves, a main shaft to which such piston-head is secured rotatably mounted in the end walls of the cylinder, curved wing mechanisms movably mounted in slots or grooves in the piston-head, rock-shafts movably mounted in the 105 piston-head—one for each of such wing mechanisms and to which such wing mechanisms are rigidly secured, a lever-arm on the end of each of such rock-shafts, and eccentric mechanisms—one arranged at each end of the pis- 110 ton-head for operating such rock-shafts by and during the rotation of the piston-head, substantially as described.

6. In a rotary engine, the combination of a cylinder provided with a fluid-pressure chamber, a piston-head rotatably mounted therein, a main shaft upon which such piston-head is mounted extending out of the end walls of the cylinder, curved wing mechanism movably mounted in grooves or pockets in the piston-head, a rock-shaft for each of such wing mechanisms movably mounted in the piston-head, a partition arranged at each end of the piston-head inclosing the ends of the fluid-pressure chamber and forming chambers between such 115 partitions and the end walls of the cylinder, an immovable eccentric arranged in such pockets, and eccentric-straps mounted thereon—one on each—and connected with the rock-shafts for operating the same by and during 120 125 130

the rotation of the piston-head, substantially as described.

7. In a rotary engine, the combination of a cylinder portion provided with a cylindrical fluid-pressure chamber, a piston-head rotatably mounted in such chamber eccentrically thereto, a plurality of piston-wings pivotally attached to such piston-head, a rock-shaft for each of such wings arranged in positive relation thereto and provided with lever-arms, a rotatable main shaft upon which the piston-head is mounted and to which it is secured extending out of the end walls of the cylinder, a stationary eccentric arranged at each end of the pressure-chamber eccentric with the main shaft and concentric with the axis of the pressure-chamber, eccentric strap and rod mechanism mounted upon such eccentrics extending outward radially from the main shaft and pivotally connected to the rock-shaft lever-arms, and a bearing portion for the main shaft adjustably secured to each of the end walls of the cylinder, substantially as described.

8. In a rotary engine, the combination of a cylinder provided with a fluid-pressure chamber, a rotatable piston-head provided with grooves, pivoted operating-wings for such grooves, eccentrics immovably secured to the end walls of the cylinder, and eccentric-straps pivotally connected with the wings to operate the same by and during the rotation of the piston-head, substantially as described.

9. In an engine of the class described, the combination of a cylinder provided with a fluid-pressure chamber and having a main fluid-inlet passage and a by-pass adapted to communicate with such pressure-chamber, a piston-head rotatably mounted in such cylinder in sliding contact with the inner surface thereof between the inner end of the main fluid-passage and the inner opening of the by-pass at a point between the main inlet-passage and pressure-chamber, wing mechanism pivotally mounted on such piston-head, and means for swinging such wing mechanism by and during the rotation of the head, substantially as described.

10. In a rotary engine, the combination of a cylinder provided with a cylindrical pressure-chamber therein, a piston-head rotatably mounted in such pressure-chamber eccentrically thereof, piston-wings pivotally attached to such piston-head, stationary cylindrical cam mechanism or eccentrics arranged in alinement with the axial center of the pressure-chamber, eccentric strap and rod mechanism mounted upon the eccentrics, and a lever-arm arranged in positive relation to each wing and pivotally connected to the eccentric-arm, substantially as described.

11. In a rotary engine, the combination of a cylinder provided with a cylindrical pressure-chamber therein, a piston-head rotatably mounted in such pressure-chamber eccentric-

ally and in contact with one side of the wall thereof, a shaft upon which such piston-head is mounted, cylindrical cam mechanism or eccentrics arranged eccentrically of the piston-head shaft and concentric with the axis of the pressure-chamber, rock-shafts pivotally mounted in the piston-head and provided with lever-arms, piston-wings mounted upon such rock-shafts and in positive relation thereto, and eccentric-arms mounted upon the eccentrics and pivotally connected with the lever-arms of the rock-shafts at a point the same distance from the axial center of the pressure-chamber as the outer edge of the wings, and thereby with the wings, for holding the outer edges of such wings constantly at the same distance from the axial center of the pressure-chamber, substantially as described.

12. In a rotary engine, the combination of a cylinder provided with a cylindrical pressure-chamber therein, a piston-head rotatably mounted within such chamber eccentrically thereto, and piston-wings each pivoted at independently-moving pivotal centers, one of such pivotal centers moving concentric to the piston-head and the other being substantially in alinement with the outer edge of the wing and movable in a true circle around the axial center of the pressure-chamber, substantially as described.

13. In a rotary engine, the combination of a cylinder provided with a pressure-chamber, a piston-head rotatably mounted within such chamber eccentric thereof, and piston-wings pivotally connected with such piston-head and also provided with attached pivot mechanism movable in a true circle eccentrically of the piston and arranged in substantial alinement with the outer edges of such wings, substantially as described.

14. In a rotary engine, the combination of a cylinder provided with a pressure-chamber, a piston-head rotatably mounted within such chamber eccentric thereof, and piston-wings pivotally connected with the piston-head and provided with pivot mechanism attached thereto movable in a true circle coincident or parallel with the outer edges thereof, and means for movably supporting such pivot mechanism and thereby guiding the outer edges of the wings in a true circle, substantially as described.

15. In a rotary engine, the combination of a cylinder provided with a pressure-chamber, a piston-head rotatably mounted within such chamber eccentric thereof, piston-wings pivotally connected with the piston-head, and crank-arms for such piston-wings rotatably mounted at a point in substantial alinement with the center of the pressure-chamber and in pivotal engagement with the wings at points in substantial alinement with the outer edges thereof, substantially as described.

16. In a rotary engine, the combination of a cylinder provided with a pressure-chamber,

a piston-head rotatably mounted within such chamber eccentric thereof, a plurality of piston-wings pivotally connected with the piston-head, and a pair of crank-arms rotatably mounted at points in substantial alinement with the center of the pressure-chamber at opposite ends of such chamber, each in piv-

tal engagement with the piston-wings at a point in substantial alinement with the outer edge of such wing, substantially as described. 10
